His Attorney.

UNITED STATES PATENT OFFICE.

LOUIS A. MAURER, OF IRVINGTON, NEW JERSEY, ASSIGNOR TO GENERAL ELECTRIC COMPANY, A CORPORATION OF NEW YORK.

SEALING-OFF TORCH.

Application filed June 4, 1928. Serial No. 643,168.

My invention relates to sealing off the bulbs of incandescent lamps and similar evacuated devices by heating the exhaust tube to fusion near the bulb, thereby hermetically sealing the bulb and at the same time detaching it from the tube, and more particularly to automatic devices for performing this operation of sealing off.

One object of my invention is to provide an automatic sealing off device which will automatically seal off a bulb, and also automatically discharge or eject the sealed off bulb. Another object is to provide a simple and rugged sealing off device which may be operated directly by the movable exhaust head or by the exhaust spider. A further object is in general to simplify and improve automatic devices of this character.

In carrying out my invention I provide an automatic sealing off device which, by the movement of the exhaust machine, is set and operated to seal off the bulb, and is subsequently operated to eject or discharge the sealed off bulb. In one form of my invention a bulb fork or holder, is moved bodily to raise the bulb and seal it off, and is afterwards tilted to eject the bulb from the fork. Both the sealing off and tilting movement of the fork are preferably, though not necessarily, produced by a lug or projection mounted on the exhaust spider, and the bulb fork is so mounted that in response to movement of the spider the fork is first moved bodily into position to receive the bulb, then released to lift the bulb, and then tilted to discharge the bulb. The sealed off bulb may be discharged in other ways than by tilting the fork, and owing to its simplicity, my invention may be used to advantage even though the sealed off bulb is not discharged automatically.

My invention will best be understood in connection with the accompanying drawing in which Fig. 1 is a side view of one form of my sealing off device with the parts in position to receive the bulb; Fig. 2 is a view at right angles to the plane of Fig. 1 showing the bulb engaging parts of the device in the same position just prior to engaging the bulb; Fig. 3 is a similar view of the same parts just after the bulb is sealed off; Fig. 4 is a similar view of the same parts with the bulb fork tilted and after the bulb has been discharged; Fig. 5 is a section along the line

5-5 of Fig. 4; and Fig. 6 is an end view 55 of the parts in the position of Fig. 4 when automatically discharging the sealed off bulb.

The exhaust machine may be of the usual type, shown in the United States patents to 60 Massey 996,936 and to Burrows 1,013,124, and comprises a rotatable exhaust spider 1 provided with exhaust heads 2 of the usual type, each of which is brought in succession 65 into sealing off position by a step by step movement of the spider. Each head receives the exhaust tube 3 of a lamp 4 which is to be exhausted. As the spider 1 rotates each lamp is automatically connected in succession to the various pumps through a flat 70 valve on which the spider 1 is carried. The exhausted lamp is sealed off while it is stationary in the position shown in Fig. 1.

The sealing off device is carried on a pedestal 5, and comprises a movable bulb 75 fork 6 for lifting the bulb away from the exhaust tube during the sealing off operation. This bulb fork is mounted so as to be movable toward the exhaust head into position to receive the bulb, as shown in Fig. 1. It is preferably mounted on the end of a rod 7 having near the other end a weight 8 which tends to move the fork away from the exhaust head 2 and thereby seal off the bulb. The rod 7 is journaled in a yoke 9 which is pivoted to oscillate on a pin 9a about an axis perpendicular to the rod 7. The fork is moved bodily toward and away from the exhaust head 2 as the yoke 9 oscillates. To move the fork automatically I 85 provide means responsive to the movement of the exhaust head and comprising a suitable connection, such as an arm 10 on the yoke in position to be engaged by an actuating member such as a lug 11 set on the exhaust spider to move the yoke and swing the fork down into position of Fig. 1 as an exhaust head approaches the sealing off position and to release the yoke so that the weight 8 will raise the fork bodily into the 90 position shown in dotted lines in Fig. 1 as the exhaust head reaches the sealing off position. The sealing off burners 12 are supplied with gas through flexible pipes 13 and are mounted to move with the fork and to 95 direct the flame between the fork and the exhaust head and upon the exhaust tube 3 at a point adjacent the bulb. As the exhaust

tube melts the weight 8 lifts the fork and bulb into the position shown in Fig. 3, thereby sealing off the bulb.

To discharge the sealed off bulb I tilt the fork by rotating the rod 7 by some automatic fork tilting means actuated by the driving mechanism of the exhaust machine. A simple and convenient way is to actuate the tilting mechanism from the exhaust spider. For example, I may mount a crank 14 on the rod 7, and connect it through a link 15 to the actuating means for tilting the bulb fork. I prefer to actuate the tilting mechanism from the exhaust spider, which may conveniently be done by means of a bell crank 16 mounted on the pedestal 5 with one end connected to the link 15 and its other end in the path of the lugs 11 on the exhaust spider. There is a lug 11 for each exhaust head, and as an exhaust head approaches the sealing-off position that lug 11 which corresponds to the preceding exhaust head catches the end of the arm 10, swings it in a clockwise direction, and then passes out from under it, thereby moving the yoke to swing the fork 6 down into the position of Fig. 1, and then releasing the yoke to permit the fork to move upward and seal off the bulb. During the movement to its next position of the exhaust head from which the bulb now in the fork 6 has just been sealed off, the lug 11 corresponding to that head strikes and moves the bell crank 16 and connected parts into the position shown in Figs 4 and 6, thereby tilting the fork and discharging the bulb into the chute 19. Further movement of the spider carries the lug 11 out from under the end of the bell crank 16, releasing the tilting mechanism, whereupon the bulb fork is returned to its horizontal position by the weight of the link 15 and bell crank 16, assisted if necessary by some means such as a spring 17, although usually the spring is not necessary. It remains in this position until the same lug 11, which a moment before actuated the bell crank 16, strikes the arm 10 and swings the fork 6 down to engage the bulb in the following exhaust head, and so on, each lug first tilting the fork 6 to discharge the sealed off bulb which has been carried in the head to which the lug corresponds, and then swinging the fork 6 down to bring it under the bulb in the following exhaust head.

What I claim as new and desire to secure by Letters Patent of the United States, is:—

1. The combination of an exhaust head intermittently movable into and out of sealing off position, a bulb fork which registers with said head in sealing off position and tends when moved out of its normal position toward said head to move back to normal position, a burner mounted to direct a flame between said fork and said head, and means responsive to the movement of said exhaust

head for first moving said fork out of normal position toward said head with its open end toward and in the path of an exhaust tube in said head and then as said head reaches sealing off position releasing said fork and leaving it free to return to normal position.

2. The combination of an exhaust head intermittently movable into sealing off position, a bulb fork in registry with the sealing off position of said head and mounted to rock perpendicularly to the direction of movement of said head with its open end toward the oncoming head and resiliently held in normal position, and means actuated in response to movement of said head toward sealing off position to rock said fork out of normal position and toward said head and to release it as said head reaches sealing off position.

3. The combination of a horizontally movable exhaust head, a bulb fork mounted to move in a vertical plane in registry with said head when it is in sealing off position and with its open end facing said head as it approaches sealing-off position and yieldingly held in normal position, and an actuating member movable with said head to engage said fork and move it away from normal position and toward said head as said head approaches the sealing in position and to automatically release said fork as said head reaches sealing off position.

4. The combination with a horizontally movable exhaust spider having a plurality of exhaust heads, a bulb fork mounted adjacent said spider to move vertically in registry with each head with its open end toward the oncoming head as each head comes in succession into sealing off position and weighted to remain in normal position, and actuating members on said spider corresponding in number to said heads and positioned to engage and move said fork out of normal position and toward each head as it approaches sealing off position and to automatically release said fork as each head reaches sealing off position.

5. The combination of a movable exhaust head, a bulb fork mounted adjacent the path of said head to rock about two axes perpendicular to each other and resiliently held in normal position against movement about either axis, and actuating means for rocking said fork about one axis out of normal position toward said exhaust head and then releasing it to permit return to normal position and subsequently rocking said fork about the other axis after the fork has rocked back about the first axis into normal position.

6. The combination of an exhaust head movable intermittently into and out of sealing off position, a bulb fork mounted adjacent the path of travel of said head to rock about two perpendicular axes and resil-

- iently held in normal position against movement about either axis, a rocking member for swinging said fork about one axis to move it out of normal position toward said head, a tilting member for rocking said fork about the other axis, and an actuating member movable in synchronism with said head to engage and release said rocking member and said tilting member in succession.
7. The combination of an exhaust head movable horizontally, a bulb fork mounted adjacent the path of travel of said head to swing vertically in registry with said head in sealing off position and weighted to remain in normal position remote from said head and also mounted to tilt from its normal position with the plane of the fork horizontal into its discharge position with said plane inclined to the horizontal, and actuating means responsive to the movement of said head to swing said fork vertically downward toward the exhaust head, release it, and subsequently tilt it into discharge position.
8. A sealing off device comprising a yoke mounted to oscillate about a horizontal axis and yieldingly held in normal position, a bulb fork mounted in said yoke to rock about an axis perpendicular to the axis of said yoke, means for oscillating said yoke, and fork tilting means for rocking said fork on its axis.
9. The combination of an exhaust head movable horizontally, a bulb fork mounted adjacent the path of travel of said head to move toward said head with the prongs of the fork horizontal and to tilt about an axis parallel to said prongs into its discharge position, and actuating means operating in synchronism with said head to move said fork toward the exhaust head and subsequently tilt it into discharge position.
10. A sealing off device comprising a movable yoke, a bulb fork mounted in said yoke to tilt about an axis in the plane of the fork, means for moving said yoke, and fork tilting means for tilting said fork about its axis.

In witness whereof, I have hereunto set my hand this 1st day of June, 1923.

LOUIS A. MAURER.
